SCAFFOLD

Rufus B. Everett, Sr., Memphis, Tenn.

Application January 23, 1951, Serial No. 207,361

2 Claims. (Cl. 304—4)

1

This invention relates to scaffolds, and more particularly to a scaffold which is suitable for use for painting, masonry work, plastering, and similar operations.

A main object of the invention is to provide a novel and improved scaffold which is simple in construction, which may be easily assembled and disassembled, and wherein the parts may be readily adjusted to change the levels thereof.

A further object of the invention is to provide an improved scaffold which involves very simple parts, which is inexpensive to manufacture, which is rugged in construction, which is safe to use, and which may be readily assembled and disassembled.

Further objects and advantages of the invention will become apparent from the following description and claims, and from the accompanying drawings, wherein:

Figure 1 is a perspective view of an improved scaffold in accordance with the present invention, shown set up for use;

Figure 2 is a transverse, vertical, cross-sectional view taken on line 2—2 of Figure 1;

Figure 3 is an enlarged, cross-sectional, detail view taken on line 3—3 of Figure 1;

Figure 4 is a cross-sectional, detail view taken on line 4—4 of Figure 3;

Figure 5 is a cross-sectional, detail view taken on line 5—5 of Figure 2;

Figure 6 is an enlarged, fragmentary, perspective, detail view showing one of the step elements of the scaffold of Figure 1, the tread member of the step element being shown separated from the riser member;

Figure 7 is an enlarged, perspective, detail view showing the top portions of one of the vertical standards of the scaffold of Figure 1, the elements of said one of the standards being shown in separated positions.

Referring to the drawings, the scaffold comprises a pair of standards shown at 11 and 12. The standard 11 comprises a pair of parallel uprights 13 and 14 secured together on opposite sides of spaced block elements 15, said block elements being uniformly spaced and defining openings 16 extending horizontally between the uprights 13 and 14. Designated at 17 is a plate member which is received between the lower ends of the uprights 13 and 14, as shown in Figure 2, and extends for substantial distances on opposite sides of the standard 11. The plate member 17 is formed with a notch 18 at its mid-portion in which is received the notched mid-portion of another plate member 19 which extends at right angles to the plate member 17 and which is generally similar in shape therewith. As shown in Figure 1, the plate members 17 and 19 define a supporting base for the standard 11 and maintain the posts defined by the uprights 13 and 14 and their intervening spacer blocks 15 in a vertical position. It will be further understood that the standard 11 may be disassembled readily by merely removing the plate members 17 and 19 from engagement with the notched lower portions of the uprights 13 and 14. From Figure 1 it will be seen that the plate member 19 is formed with the relatively large, upwardly opening notch 20 at its intermediate portion which receives the notched lower ends of the uprights 13 and 14, and which also receives the notched intermediate portion of the plate member 17, as above described.

Secured to one outer end of the plate member 17 is a vertical upstanding bar member 21 which is formed with the spaced openings 22. Designated at 23 and 24 are respective horizontal bar members which are detachably secured to the upstanding bar member 21 by pin members 25 and 26 extending through the bar members 24 and 23 and through adjacent openings 22 in the vertical bar member 21, as shown in Figures 1 and 2, the bar members 23 and 24 having reduced ends 27 and 28 which are received in successive spaces 16 of the standard 11 and which are locked therein by pin members 29 extending through the reduced bar portions 27 and 28 and openings 30 provided in the uprights 13 and 14. It will be readily understood that the bar members 23 and 24 may be detached by removing the respective pin members 25, 26 and 29.

Designated at 31 and 32 are respective parallel, vertical uprights forming the main portion of the standard 12, said uprights being secured through spaced block members 33 arranged similarly to the block member 15 of the standard 11. The lower ends of the uprights 31 and 32 are interlocked with respective, transversely arranged plate members 17' and 19', said plate members 17' and 19' being notched in the same manner as the plate members 17 and 19, and the lower ends of the uprights 31 and 32 being notched to interlock with the transversely arranged plate members 17' and 19' in the same manner as in the case of standard 11. From Figure 1 it will be noted that one side of the plate member 19' has a horizontal top edge 34 and that a vertically rising plate member 35 is secured to the plate member 19' adjacent the upright 31. The plate member 35 is formed with the upwardly facing,

40
45
50
55

vertical notch 36. Designated at 37 is a step member having a tread portion 38 and a notched riser portion 39 adapted to lockingly engage in the notch 36 of the vertical plate member 35 in the manner shown in Figures 1 and 6, thereby detachably securing the step member 37 in the position shown in Figure 1. Similarly, the outer portion of the plate member 19' is formed with an upwardly opening, vertical notch which is adapted to lockingly engage with the notched lower portion of another step member 37', as shown in Figure 1.

Secured to one outer end of the plate member 17' is a vertical bar member 40 formed with the spaced openings 41. Designated at 42 is a bar member which is releasably secured at one end to the bar member 40 by a removable pin 43 and which is received between adjacent blocks 33 of the standard 12. The pin member 43 may be inserted through a selected opening 41 of the vertical bar 40. Designated at 44 is a horizontal, elongated roller which is rotatably mounted on a length of pipe 45, said length of pipe being suspended from the bar member 42 by a chain 46 passing through the pipe 45 and extending through openings 47, 47 formed in the opposite end portions of the bar member 42. The chain member is secured at 48 in any suitable manner, as for example, by providing a hook on the end of the chain member which may engage with a link of the chain. Designated at 49 is a board having one end portion received between the bar members 23 and 24 and having its other end portion received between the bar member 42 and the roller 44. Pivoted at 50, 50 to the bar member 42 are respective eccentric discs 51, 51 which extend below the bottom edge of the bar member 42 and which lockingly engage with the top surface of the board 49, preventing said board 49 from rising vertically and securing the board against vibration. In the position shown in Figure 3, the eccentric disc members 51, 51 exert a frictional clamping action on the board 49 and secure said board against moving lengthwise. However, when it is desired to remove the board 49 from the scaffold, the eccentric rollers 51, 51 are rotated to elevated positions, thereby releasing the board 49 and allowing the board to be withdrawn lengthwise from the scaffold.

Designated at 52 is a shelf board which is supported on respective bar members 53, 53 received between successive blocks 15, 15 of standard 11 and successive blocks 33, 33 of standard 12 and releasably secured by respective pins 54 and 55. The pin 54 extends through aligned openings 30 in the uprights 13 and 14 of standard 11 and extends through an opening in the end portion of the bar member 53. The pin member 55 extends through aligned openings in the uprights 31 and 32 of standard 12 and extends through an opening in the end portion of the other bar member 53. The bar members 53, 53 may be readily detached by removing the pin members 54 and 55. The board 52 provides a shelf for any desired materials for use in the work being done, such as bricks, mortar, paint and the like.

Designated at 56 and 57 are respective plate members having reduced, horizontally extending portion received between adjacent blocks 15, 15 at the upper end of the standard 11 and adjacent blocks 33, 33 at the upper end of the standard 12 and detachably secured in the upper ends of the respective standards 11 and 12 by removable pins 58. The outer portions of the plate members 56 and 57 are formed with vertical, upwardly facing

notches 59 which lockingly receive notched end portions of a rail member 60. Designated at 61 is a tray member to the opposite edges of which are secured the respective notched block members 62, 62 which slidably engage the top margin of the rail member 60. The tray member 61 is employed for supporting plastic material, such as plaster, mortar, or the like, said tray member being slidable from one end of the scaffold to the other, whereby the plastic material may be moved to any convenient position relative to the worker using the scaffold. It will be readily apparent that the rail member 60 and its supports 56 and 57 may be readily detached from the uprights 11 and 12 when it is desired to disassemble the scaffold.

When the scaffold is set up in the manner shown in Figure 1, the worker may conveniently mount the scaffold by ascending the steps 37' and 37 and stepping upon the board 49. The position of the board 49 may be changed as the work progresses to any desired height by engaging the ends of the bar members 23 and 24 in suitable spaces 16 of standard 11 and shifting the connections of said bar members with the vertical upright 21, and by similarly changing the position of the opposite bar member 42 so as to maintain the board 49 in a horizontal position.

While a specific embodiment of an improved scaffold has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A scaffold comprising a pair of vertical standards, each standard being formed of a pair of spaced uprights having spaced blocks therebetween forming uniformly spaced horizontally extending openings therethrough, a supporting base for each standard, respective vertical support bars secured to the supporting base portions of said standards and spaced outwardly from said standards, a pair of horizontal bar members secured to one of the vertical support bars and received in adjacent horizontally extending openings of the associated standard, an additional horizontal bar member secured to the other vertical support bar and received in a horizontally extending opening of its associated standard, a board disposed adjacent one end thereof between said first-named pair of horizontal bar members and disposed adjacent its other end below said additional horizontal bar member, an elongated horizontal roller secured to said additional horizontal bar member and disposed beneath said board, a plurality of eccentric discs secured to said last named bar member engaging said board to limit upward movement thereof, a further pair of horizontal bar members received in the openings of said standards, a horizontal shelf board supported on said further pair of horizontal bar members, a still further pair of horizontal bar members received in the openings of said standards above said shelf board, said last-named bar members being formed with upwardly opening vertical notches, a rail board received in said notches, and a tray member slidably mounted on said rail board for sliding movement along said shelf board.

2. A scaffold clamp for use with a scaffold having a pair of vertical standards, a pair of horizontal bar members secured to one of the

vertical standards, and a board received between said bars, said clamp comprising an additional horizontal bar member adapted to be secured to the other standard, an elongated horizontal roller secured to said additional horizontal bar member and adapted to be disposed beneath said board, and a plurality of depending disc members eccentrically pivoted to said additional horizontal bar member and arranged to engage said board to limit upward movement of the board.
